UNITED STATES PATENT OFFICE.

HENRY A. WEIHMANN, OF PHILADELPHIA, PENNSYLVANIA, ASSIGNOR TO
SIMONS, BROTHER & CO., OF SAME PLACE.

DESIGN FOR A CANE OR UMBRELLA HANDLE.

SPECIFICATION forming part of Design No. 19,989, dated July 1, 1890.

Application filed April 15, 1890. Serial No. 348,083. Term of patent 3½ years.

To all whom it may concern:

Be it known that I, HENRY A. WEIHMANN, a citizen of the United States, residing in Philadelphia, in the county of Philadelphia and State of Pennsylvania, have invented and produced a new and original Design for Cane or Umbrella Handles, of which the following is a specification, reference being had to the accompanying drawing, forming part thereof.

10 In the drawing is shown a side elevation of a cane or umbrella handle illustrating my new design.

15 A is the body part, and is like an inverted frustum of a cone, but with a very slight taper.

20 This body part is mounted on the top with the rounded cap B of plain surface and on the bottom with the annular band H of ornamental work. The body is provided on its upper and lower portions with oblique ornamental ribs E, which cross at the part marked G, leaving a space to one side, which is en-

circled by an ornamental raised portion F, inclosing a plain surface D. The spaces bounded by the ribs E are indicated at C, and decrease in size from the top of the handle to 25 the bottom, and are plain.

The general effect of the handle is illustrated in the drawing, which shows one side only, the other side being exactly the same.

25 The handle is made of any suitable material.

Having now described my new design, what I claim as new, and desire to secure by Letters Patent, is—

30 The design for cane or umbrella handles, 35 substantially as herein described and shown.

In testimony of which invention I have hereunto set my hand.

HENRY A. WEIHMANN.
